ARTICULATED RAIL CAR STRUCTURE

William L. Davis and Alfred O. Williams, Battle Creek, Mich., assignors to Clark Equipment Company, Buchanan, Mich., a corporation of Michigan

Application October 30, 1940, Serial No. 363,462

7 Claims. (Cl. 105—4)

This invention relates to articulated rail car structures, and is concerned more particularly with the provision of a resilient articulation buffer to be used between the adjacent end frame sections of the car bodies of an articulated train, such as a passenger train, elevated or subway train in which the adjacent ends of two car sections are mounted on a single truck.

Heretofore in cases where a tight coupling between the car sections is provided, it has been customary to employ manganese steel blocks which were supposedly located in abutment to prevent bumping between the two car bodies during rapid acceleration or deceleration. However, we have found that it is impossible to locate the contact points on these blocks in such manner that slack will not occur. Even if they were perfectly located, wear therebetween due to the articulation between the cars would occur, and banging of the two car bodies together would start at some period during the life of the cars. This wear is cumulative, and consequently would increase rapidly as time went on. The provision of slack between the blocks due to wear or imperfect location is undesirable, both from the standpoint of passenger comfort, undue noise and increased wear on the bearing by which the two cars are pivotally connected together. Consequently, it is extremely desirable to eliminate any possibility of slack occurring between the contact blocks.

The present invention therefore has, as one of its primary objects, to provide a non-metallic resilient buffer arrangement between the blocks which will take up all ordinary coupling stresses by the absorption of such stresses within the rubber members so that the blocks are employed only for the most severe shocks, such as collision or high frequency impacts.

A further object of the present invention is to provide a construction in which rubber plates or discs are secured to the adjacent ends of the car frames, and are set up, when the cars are coupled together, under an initial compression which insures maintenance of the contact between the rubber and resistance to relative movement between the car ends sufficient to prevent contact of the blocks under normal relative movement between the bodies.

A still further object of the present invention is the provision of a structure in which suitable mechanism is provided on the end of the car body to facilitate placing the rubber plates under initial compression, this mechanism comprising jacking screws for placing the plates under initial

compression with means for shimming the supporting member to maintain such compression.

Another feature of the present invention is the provision of a simplified structure for accomplishing this result which is readily adaptable to car end sections of the type now in general use, so that the invention may be applied to cars already built, as well as to new car structures.

Other objects and advantages of the present invention will appear more fully from the following detailed description which, taken in conjunction with the accompanying drawings, will disclose to those skilled in the art the particular construction and operation of the preferred form of the present invention.

In the drawings:

Figure 1 is an elevational view, partly in section, showing the coupling between the two car ends and embodying the present construction;

Figure 2 is a top plan view, partly in section, of the construction shown in Figure 1; and

Figure 3 is an end view taken substantially on line 3—3 of Figure 2, showing in detail the buffering arrangement.

Considering now the drawings in detail, the end frame member of one car body is indicated generally at 5, and includes a depending pedestal member or portion 6 in which is mounted the kingpin sleeve or tubing 7 which fits into the kingpin receiving bolster of the car truck. The end frame member 5 is also provided with a substantially annular cup-shaped portion 8 in which is located a spherical bearing seat 9, this bearing seat being preferably formed of a suitably hardened steel member which is adapted to receive the partial spherical bearing portion 10 carried by the end frame portion 12 of the adjacent car body. Preferably, the end frame portion 12 of the adjacent car body is provided with an annular laterally directed channel-shaped lip 13 of semi-cylindrical form, which is adapted to receive a safety chain having its ends secured to the trunnions 14 carried by the end frame member 5.

From the construction thus far described, it is apparent that the bearing portion 10 of the car frame member 12 has sliding pivotal movement within the bearing portion 9 of the car frame end 5, whereby the two car bodies are articulated together about the center line of the kingpin 7 for relative pivotal movement about curves or the like. This construction is somewhat similar to that described in the copending application of Alfred O. Williams, Serial No. 302,279, filed November 1, 1939.

As seen clearly in Figure 2, the car frame member 5 is provided with a transverse web portion 15 which has welded thereto at the outer ends the wedge-shaped blocks 16 forming abutments for jack screws 17 carried in the tip portions 18 welded to the end flange portions of the abutment member 19. The member 19 at the end adjacent the car frame member 12 is provided with a planar face portion 20 terminated at its lateral edges by the forwardly directed flanges or lips 22. Seated within the recess thus formed is a steel plate 23 in which is secured the shouldered portion 24 of a manganese steel buffering block 25. Disposed about the block 25 and projecting axially beyond the spherical contact face thereof is a rubber buffering member 26 which, as shown in Figure 3, may be of square form and is vulcanized directly to the face of the steel plate 23 about the block 25, the rubber member 26 being apertured to receive the block 25.

The rubber member 26 is preferably square in plan view and, by being vulcanized directly to the plate 23, is securely attached thereto to project axially forwardly beyond the contact surface of the block 25. The plate 23 is secured to the face 20 by means of the studs 27, there being four such studs provided.

Similarly, the outer end of the car frame section 12 is provided with a face portion 30 parallel to the face 20 and provided at its lateral edges with flanges or lips 32 forming a recess for receiving the steel plate 33. The plate 33 has a central aperture which receives the shoulder portion 34 of a second manganese block member 35, also provided with a spherical contact surface. Vulcanized to the face of the plate 33 about the block 35 is a square block of rubber 36, which also projects forwardly axially beyond the contact face of the block 35. The rubber member 36 is substantially of the same shape as the plate 33 and, by being vulcanized to the face of this plate, is secured directly thereto. The blocks 26 and 36 are identical, as are the manganese contact blocks 25 and 35, thus providing an economical structure.

In assembling this buffering structure, the portion 10 of the car end frame 12 is first seated in the bearing portion 9 of the adjacent end frame 5 to provide the pivotal connection therebetween each of the faces 20 and 30, being first provided with the plates 23 and 33 secured thereto by the studs 27 and 37, respectively. At this time, the member 19 is disposed with its flange faces 38 in direct abutment with the end flange 15 of the end section 5, thus providing for clearance between the block members 26 and 36. Upon tightening of the jacking screws 17 against the abutments 16, the member 19 is moved axially toward the end frame 12, thereby producing compression of the contact faces of the rubber blocks 26 and 36. Preferably, such compression is increased by means of the jacking screws 17 until the total pressure of about 2,000 pounds is exerted, which, due to the relative areas in contact, produces a compression of around 65 pounds per square inch between the rubber blocks. This also provides for the forming of a spacing chamber 40 between the contact surfaces of the manganese blocks 25 and 35, providing the necessary clearance therebetween so that during the ordinary normal relative motion between the bodies, these contact surfaces will not come into contact.

When the desired pressure has been built up between the rubber blocks, suitable shims 42

are interposed between the flanges 33 of the member 19 and the flanges 15 of the member 5, these shims thereby relieving the screws 17 from the necessity of maintaining the compression. 5 With the shims in place, suitable bolts 43 are employed to couple the member 19 rigidly to the member 5, these shims maintaining the desired pressure between the blocks 26 and 36. The assembly is thereby completed, and it will be noted that the rubber blocks 26 and 36, as shown in Figure 2, are compressed, causing a slight bulbing of the rubber, this compression still maintaining the desired clearance between the manganese steel blocks 25 and 35. Preferably, such clearance is maintained at about one-eighth of an inch so that ordinary normal coupling movements between the cars will not cause contact between the blocks, thus preventing any wear on the blocks except under the most severe conditions of coupling or collision.

The rubber blocks being under compression and being flexible allow articulation of the car bodies without undue pressure being placed on the rubber, and provide a non-metallic and noise-deadening connection between the adjacent end frame sections whereby the clattering normally occasioned when a train accelerates or decelerates due to slack in the coupling is eliminated. This provides a very quiet resilient connection between the articulated end sections of the car bodies, the rubber accommodating the relative angular movements between the car bodies without allowing the manganese steel blocks to come into contact.

It is therefore believed apparent that we have provided a novel type of resilient articulated buffer construction for rail cars and the like, which is of simple design and is capable of easy assembly and disassembly, and also is adaptable to large numbers of articulated cars now in use.

We are aware that various changes may be made in certain features of the present construction without in any way departing from the underlying principles thereof, and we therefore do not intend to be limited except as defined by the scope and spirit of the appended claims.

We claim:

1. In an articulated coupling for car bodies including end car sections terminating in parallel transverse end walls, plate members secured to adjacent faces of said walls and having central apertures, buffering blocks secured in said apertures and projecting toward each other with their axes in longitudinal alignment, and rubber members vulcanized to the faces of said plates about said blocks and extending beyond the extremities thereof, said blocks being maintained in abutment under pressure to provide clearance between the adjacent contact faces of said blocks during normal articulation of said car bodies.

2. In an articulated coupling for car bodies, said bodies having end sections pivotally mounted together and having parallel end walls above the pivotal mounting, buffering blocks carried by said end walls and having adjacent spherical contact surfaces, said blocks having their axes in longitudinal alignment, and rubber plates carried by each end wall extending about said blocks and projecting outwardly beyond the extremity thereof, said plates being of a thickness such that when maintained under compression in abutting engagement with each other said surfaces of said blocks are maintained out of con-

tact during normal articulating movement of said end sections.

3. In combination, a first car end section having a transverse end wall, a plate secured thereto carrying a projecting steel buffering block having a spherical contact surface, a resilient non-metallic disc secured to said plate extending around said block and of a thickness so as to extend appreciably beyond the projection of said block, a second car end section, a member secured to said section and having an end wall parallel to said first end wall, a corresponding longitudinally aligned buffering block and disc carried thereby, said blocks being out of contact during normal articulation of said end sections, and means between said second car end section and said member for moving said member toward said first car end section to produce a predetermined pressure between the faces of said discs while said blocks are still maintained out of contact.

4. The combination, in an articulated car body mounting wherein the adjacent end sections of the car bodies having parallel transverse end walls, of a buffer arrangement therebetween comprising steel buffering blocks carried by each of said walls and projecting toward each other, said blocks being in alignment longitudinally of the car body, resilient non-metallic plates surrounding said blocks and of a thickness such that the faces of said plates when in abutment under compression maintain said blocks out of contact during normal relative movement of said end sections, and means for maintaining said faces under predetermined compression.

5. The combination, in an articulated car body mounting wherein the adjacent end sections of the car bodies having parallel transverse end

walls, of a buffer arrangement therebetween comprising longitudinally aligned steel buffering blocks carried by each of said walls and projecting toward each other but out of contact during normal articulation of the car bodies, rubber plates carried by said end walls extending about each of said blocks and having a predetermined thickness whereby they project outwardly beyond the extremities of said blocks when in abutment,

5 10 and means on one of said end sections for producing a predetermined compression between the faces of said plates, said plate thickness being such that even under said compression said blocks are maintained out of contact.

15 6. In combination, in an articulated car structure in which the end sections of adjacent cars are mounted on a common pivot, buffering means between said end sections comprising buffering blocks projecting toward each other with their axes in longitudinal alignment and carried on 20 the respective end sections, said blocks being out of contact during normal articulation of said end sections, rubber means on each of said end sections extending about said blocks and projecting beyond the extremities thereof into abutting engagement with each other, and means on one end section for placing said rubber means in predetermined compression between said sections.

25 7. The combination of claim 6 wherein said last-named means includes a member bolted on said one end section, and means for moving said member longitudinally toward the other end section and shimming it in position to maintain said compression.
